SIGNALING SYSTEM

John H. Cook, Rock Island, Ill.

Application September 28, 1943, Serial No. 504,169

2 Claims. (Cl. 177—314)

This invention relates to a signaling system and while it is primarily designed as a burglar alarm for use in banks and other places, it is to be understood that it can be employed wherever it is desired to maintain a signal system in operative condition even though a portion of the apparatus should become inoperative because of intentional cutting of the circuit, or short circuiting or some other causes.

Another object is to provide a signaling system which is simple and dependable and which, in the event of trouble in the main circuit, can quickly be placed in service even though under normal conditions the apparatus would become inoperative.

A still further object is to provide a signaling system made up primarily of metallic circuits sections of which can be grounded, when desired, for test purposes.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown, the apparatus being illustrated as combined with a money drawer whereby, when an attempt is made to remove the drawer or to remove money from the drawer, or when the circuit is intentionally closed by a push-button or the like, the system will be operated.

In said drawings

Fig. 1 is a circuit diagram showing structure forming part of the invention.

Figure 2 is a top plan of the money drawer and attendant parts.

Figs. 3 and 4 are sections taken, respectively, on the lines 3—3 and 4—4 of Fig. 2.

Fig. 5 is an elevation of the circuit-controlling parts.

Fig. 6 is a top plan of the structure depicted in Fig. 5.

Fig. 7 is a transverse section of the structure shown in Fig. 5.

Fig. 8 is a longitudinal section taken adjacent the electro-magnet, parts being broken away.

Fig. 9 is a section on the line 9—9 of Fig. 5.

Referring to Figs. 2, 3 and 4, there is shown a money box 1, comprising a double-layer bottom 2, side walls 3, and a double-layer inner end

wall 4. The inner layer of the end wall 4 is not quite so high as the outer wall thereof, thereby presenting a horizontal shoulder 5.

A partition 6 extends across the money box 1, and defines therein a rear compartment 7. A lid 8 closes the upper end of the compartment 7 and rests upon and is secured to the partition 6, the side walls 3 and the shoulder 5, the lid abutting against the upstanding portion of the outer layer of the end wall 4. The partition 6 and the lid 8 have aligned slots 10.

The upper layer 11 of the bottom of the money box extends from the open front 12 of the box, backwardly to the partition 6. The upper layer 15 has a longitudinal opening 14, closed at its lower end by the lower layer of the bottom 2.

A post 15 is located in the compartment 7, and is fixed in the angle defined by the partition 6 and one of the side walls 3. A block 16 forms part of the end wall 4 and is of less height than the inner layer of that wall, to leave a space between the upper surface of the block and the lid 8. An insulating sheet 17 is secured to the forward surface of the block 16, and extends between the side walls 3 and between the lid 8 and the lower member of the bottom 2, and forms a forward closure for the space above the block 16.

A box-like money drawer 18, open at its top and at its rear end, is mounted to reciprocate in the money box 1, on the upper layer 11 of the bottom 2 of the box, and when fully closed, the drawer abuts against the partition 6, the drawer being adapted to receive a stack M of paper money or other thing of value and not to be stolen.

A transverse shaft 19, located in the compartment 7, has its end portions mounted to rock in the side walls 3 of the money box 1, and is supplied intermediate its ends with a forwardly presented arm 20, passing through the slot 10 of the partition 6. The arm 20 is downwardly concaved in its intermediate portion 21, to rest on the stack M of money in the drawer 18, and to provide an elongated finger piece 22, facilitating the lifting of the arm by an operator, when money or the like is to be placed beneath it.

In order to constrain the intermediate portion 21 of the arm 20 to bear yieldably on the stack M of money, a portion of the shaft 19 is surrounded by a coiled spring 23, the inner end of the spring being engaged with the arm 20, the outer end of the spring bearing upon a wear plate 24 on the post 15.

A keeper 25 is mounted on the shaft 19, for adjustment circumferentially thereof, and is held

in adjusted positions by a set screw 26, threaded into the keeper and engaging the shaft. The keeper 25 has a peripheral seat 27, in which is adapted to engage, the upper portion of a spring latch 28, having its lower end secured at 29' to the post 15. The purpose of the keeper 25 and the latch 28 is to hold the arm 20, releasably, in a substantially vertical, elevated, out-of-the-way position, against the action of the spring 23, should the operator desire.

Conductor connectors 29 and 30 are secured to the upper surface of the block 16 of the money box 1. Likewise secured to the block 16 is the offset foot 31 of a spring tongue 32 constituting the operating switch. The free end of the tongue 32 is spaced from, but is adapted to engage, an adjustable contact screw 33, threaded into a conductor connector 34, secured to one side wall 3 of the money box 1.

A cam 35 is adjustable circumferentially of the shaft 19, but is fixed thereto by a set screw 36, threaded into the cam. The cam 35 is located underneath but normally out of contact with the spring tongue 32, and is so located as to raise the free end of the tongue and cause it to make contact with the screw 33 or its equivalent. This action occurs if the arm 20 is lifted to release money or if the drawer is pulled out. In the latter case the arm 20 will drop into recess 14, rotate the cam 35 and make a contact between tongue 32 and screw 33.

A resilient brush 37 is provided and bears against the shaft 19, the lateral foot 38 of the brush being secured to the lower layer of the bottom 2 of the money box 1 and passing under the block 16.

Passing to Figs. 5 to 9, there is shown a base 39, to which is secured a standard 40. The numeral 41 marks an electro-magnet, the core 42 whereof is mounted at one end on the standard 40. The electro-magnet 41 is received in an eye 43, forming part of an upright 44 on the base 39 and provided at its upper end with an inverted, U-shaped bracket 45. The base 39 carries connectors 71, 78, 79 and 80.

An armature base 46 is secured to the part 39 and has upstanding, terminal ears 47. Bearing screws 48 are threaded into the ears, and are held in adjusted positions by lock nuts 49.

A shaft 50 is mounted to rock on the bearing screws 48. Intermediate its ends, the shaft 50 carries an upwardly extended armature 51, which can swing as the shaft 50 rocks about its axis, the armature carrying a part 52, which is responsive to the core 42 of the electro-magnet 41.

A post 53 is erected on the base 39 and has a bearing 54 at its upper end, a winding shaft 55 being frictionally held in the bearing, the winding shaft being rotated by a hand wheel 56 thereon. One end of a pull-spring 57 is secured to the armature 51, the opposite end of the spring being attached to a flexible element 58, wound about and secured to the shaft 55.

The effort of the spring 57 is to retract the armature 51 with respect to the electro-magnet 41, and the effectiveness of the spring may be varied by rotating the shaft 55. The movement of the armature, away from the electro-magnet, is limited by an insulated stop screw 59, threaded into the bracket 45, and held against rotation by a lock nut 60.

A transversely extending piece of insulating material 61 is mounted on the eye 43 of the upright 44, and to the insulating material is secured an L-shaped support 62. A resilient

tongue 63 is secured at its outer end to the support 62. A contact screw 64 is threaded into the bracket 45, and is held in adjusted positions by a lock nut 65. The inner end of the resilient tongue 63 extends between the screw 64 and the armature 51.

A cross-arm 66 is secured to the armature 51. On opposite sides of the electro-magnet 41 are located normally open switches, one switch comprising a pair of upstanding spring strips 67 and 68, the other switch comprising a pair of upstanding spring strips 69 and 70. The lower ends of the strips 67-68-69-70 are secured to the base 39. The strips 67 and 69 are of such height that they may be engaged by the cross-arm 66 on the armature 51.

Referring to Fig. 1, the numeral 71 indicates a secondary circuit in which is interposed an audible signal 72, and a source 73 of electrical energy. The switch strips 69 and 70 are interposed in the signal circuit 71, and that circuit is normally open.

The numeral 74 indicates a secondary circuit in which is interposed a visible signal 75, and a source 76 of electrical energy. The switch strips 67 and 68 are interposed in the signal circuit 74, and the circuit 74 is normally open.

At 84 there appears one source of electrical energy included in a main metallic circuit and to be included in the first section of said circuit when split as hereinafter explained. To one side of this source 84 is connected a conductor 85, joined to a connector 79, and to the connector is joined one end 86 of a winding 87 disposed about the core 42 of the electro-magnet 41. The opposite end 88 of the winding 87 is joined to a connector 77.

From the connector 77, a conductor 89 leads to the connector 29 on the money box 1, a small resistance 113 and a single-pole, single-throw, normally closed switch 90 being interposed in the conductor 89. A conductor 91 is joined to the connector 29 and to the connector 34 which carries the contact screw 33.

To the foot 38 of the brush 37 is joined a conductor 92, connected to the member 30, and from the connector 30, a conductor 93 leads to a ground 94.

From the opposite side of the source 84, hereinbefore mentioned, a conductor 97 extends, and is connected to the cross-piece 46, which supports, and is electrically assembled with, the shaft 50 and the armature 51.

From the base 46, a conductor 98 leads to a ground 99, a normally closed switch 100 being interposed therein.

At 101 there appears another source of electrical energy forming a part of the main metallic circuit and adapted, when the circuit is split as hereinbefore explained, to be included in the second section of said circuit. One side of this source is connected at 111 to the base 46. To the opposite side of the source 101 is connected a conductor 102, in which a small resistance 114 is interposed, the conductor 102 leading to the connector 78, and to the connector 78 is joined one end 103 of a second winding 104, disposed about the core 42 of the electro-magnet 41 in parallel relation to the winding 87. The opposite end 105 of the winding 104 is joined to the connector 80.

From the connector 80 extends a conductor 106, a normally closed, single-throw, single pole switch 107 being interposed in the conductor 106. The conductor 106 is joined to the foot 31 of the spring tongue 32 on the money box 1, and since the parts

31 and 32 are integral, they are electrically connected, as indicated diagrammatically at 112 in Fig. 1.

The tongue 63 of Figs. 6, 5 and 1, has joined thereto by way of the support 62, a conductor 108, the conductor 108 being joined to the switch 107. A conductor 109 is connected electrically to the screw 64, and to the conductor 89 in the vicinity of the switch 90. A normally closed single-throw, double-pole switch 110 is interposed in the conductors 108 and 109 and is located between the switches 90 and 107 on the one hand, and the tongue 63, the screw 64 and the tongue 63, on the other hand.

Under normal conditions the various switches 90, 100, 107 and 110 are closed and the switch formed by the spring tongue 32 is out of contact both with the contact 33 and with the cam 35.

The installation shown and described, shows the signal apparatus combined with a money drawer. Thus should an attempt be made to remove some of the money from the drawer by first lifting the arm 20, or by removing the drawer so as to permit the arm 20 to drop, the apparatus would promptly operate as follows:

Arm 20, when shifted, will move the cam 35 against the tongue 32 thereby establishing a contact between the tongue and the ground and also a contact between the tongue and the part 33. As a result of this operation the primary metallic circuit will be closed. This circuit, starting at 84, extends through the connections 85, 79 and 86 to the coil 87 and thence through the connections 88, 77 and 89, 29 and 91 to contact 34-33. Assuming that 33 is in engagement with tongue 32 which has been lifted by the movement of cam 35, the circuit continues by way of connections 112, 31, 106, 80, 105 and coil 104 through connections 103, 78, 102 and 114 to battery 101. The positive pole of this battery 101 is connected at 111 to the base 46 which, in turn, is electrically connected as at 97 to the negative pole of battery 84 so that the circuit thus is completed. As the metallic circuit thus completed is more efficient than a grounded circuit, the fact that base 46 is grounded through connection 98 and that cam 35 is grounded through connections 37, 92 and 93, will not affect the operation of the circuit.

The instant the metallic circuit is closed as explained, the electro-magnet is of course energized and attracts the armature 51, causing it to make contact with the tongue 63 and force said tongue into engagement with the contact screw 64. Under normal conditions, prior to energizing the electro-magnet, there is no circuit established through the connections 108 and 109. When the electro-magnet is energized, however, and the tongue 63 brought into engagement with armature 51 and contact screw 64, the current from battery 101 flows through connection 111 to base 46 and thence through armature 51 to tongue 63, connection 108, switch 110 and connection 106 to coil 104 and then by way of connections 103, 78, 102, and 114, back to the battery 101. At the same time a circuit is set up from battery 84 through connections 113, 85, 79 and 86, to coil 87 and thence through connections 88, 77 and 89 to connection 109, back through switch 110 and connection 109 to contact screw 64, tongue 63, armature 51, base 46 and connection 97 to the negative pole of battery 84. Consequently the electro-magnet is energized by separate circuits from the respective batteries after it has first been energized by the two batteries in series. Therefore, should either of these secondary circuits of the

two batteries become broken from any cause, the remaining battery would continue to maintain the electro-magnet in its energized condition so that the armature 51 would be held pressed against tongue 63 and hold it, in turn, pressed against the contact screw 64.

By means of the switches 110, 107, 90, and 100, various parts of the circuit can be tested from time to time in an effort to locate any break which may have occurred therein.

It is to be understood that every time the armature 51 is attracted by its magnet, the two circuits containing the respective batteries 84 and 101 will be closed by the member 52, thereby energizing the respective signal devices.

Should the contact at 33, 32 and 35 be open at the time the individual circuits of either of the batteries 84 and 101 is broken, the signal devices would still operate upon the closing of the circuit at 32-33. For example, assuming that the connection 111 has been broken, the closing of the circuit at 32-33 would result in the flow of current from battery 84 through connections 85, 79 and 86 to coil 87 and thence by way of connections 88, 77 and 89 to connection 91, contact 33, tongue 32, shifting element 35 and connections 37, 38, 92, 30 and 93 to ground. As the negative pole of battery 84 is connected to ground by way of the connections 97, base 96, 98, and switch 100, a grounded circuit thus would be established sufficient to energize the electro-magnet and actuate the armature 51 with the result that both signal circuits would be closed.

Should the break occur, for example, at 97, the closing of the circuit between 32 and 33 would result in flow of current from battery 101 through connection 111 to base 46 and thence to ground by way of connections 98 and 100. The negative pole of battery 101, however, would be connected to ground by means of the conductors 114, 102, 103, coil 104, connections 105, 106 and 112 to tongue 32 and thence by way of the elements 35, 37, 38, 92, 30 and 93 to ground at 94. Thus the grounded circuit would be completed through battery 101 and the electro-magnet would be energized even though battery 84 should be out of service.

The switches 90, 100, 107 and 110 have been provided primarily for test purposes. Normally they are closed. Tests are made as follows:

First.—By opening the switch 100 the continuity of the conductors 89-106 can be tested. If this switch is open and the money box mechanism is operated, the signals will be energized if the metallic circuit is in working condition. If the switch 100 is closed and connection 106 shorted, the switch 107 should be opened and the money box mechanism operated. This will bring in the signals by closing a ground circuit which leads from the source 84 through connections 85 and 86 to the winding 87 and thence by way of the connections 88, switch 90 and tongue 32 to the ground. The negative side of the source 84 is connected at 97 to base 46 and thence to ground. Thus if the connection 106 should be interfered with or switch 107 be opened, the winding 87 will act to energize the magnet and cause the signal devices to be energized.

Second.—Should the connection 89 be either broken or grounded, the switch 90 is opened and the other ground circuit will be established when closed by the tongue 32. This circuit would include the connection leading from the source 101 to the base 46 to ground and from the negative terminal of the source through connections 102.

winding 104 and connections 105, 106 and 32 to ground. Thus one of the secondary or signal circuits would remain closed even though the connections 106 and/or 89 should be broken and the location of the break can be located by tests in which the respective switches 90 and 107 are separately opened.

From the foregoing it will be noted that normally there is maintained a metallic circuit which is closed by removal of the drawer 18 or by lifting arm 20 to a position above normal for the purpose of removing money from beneath it or for locking it in fully raised position. The circuit can also be closed by a push-button 113 or other switch suitably located whereby the signaling system can be operated in the event of fire or other emergency. Should either the connection 89 or the connection 106 become broken, the remaining side of the circuit which was not broken will be grounded at 99 through connection 100 so that shifting of the cam will result in operation of the signaling system, one side of the circuit being metallic while the other side is ground. In case of a short between the connections 89 and 106, however, it would be necessary to open either switch 90 or switch 107. Either would clear the trouble and the same procedure should be followed in the event of a ground in either connection 89 or connection 106, whichever clears the trouble. The switches 90, 107, 100 and 110 may also be manipulated for testing the apparatus to determine whether the various parts thereof are in working condition.

It is to be understood of course that switch 110 is used for breaking the independent metallic circuits after they have been established and for the purpose of discontinuing the functioning of the signaling elements.

What is claimed is:

1. In a signal apparatus the combination with a normally open signal circuit, of an electromagnet having separate coils, an armature for the magnet positioned to close the signal circuit when the magnet is energized, an actuating element normally grounded, a normally open switch positioned for actuation by said element, said switch including a tongue and a contact cooper-

ating with the tongue, an electrical connection between said contact and one end of one of the coils, a battery having its positive pole connected to the other end of said coil and its negative pole connected to the armature and to ground, an electrical connection between the tongue and one end of the other coil, a second battery having its negative pole connected to the other end of said second coil, a grounded electrical connection between the positive pole of said second battery and the connection between the negative pole of the first battery and the armature, and means operated by the movement of the armature when its magnet is energized, for dividing the apparatus into two independent circuits each including one of the batteries and one of the coils.

2. In a signal apparatus the combination with a normally open signal circuit, of an electromagnet having separate coils, an armature for the magnet positioned to close the signal circuit when the magnet is energized, an actuating element normally grounded, a normally open switch positioned for actuation by said element, said switch including a tongue and a contact cooperating with the tongue, an electrical connection between said contact and one end of one of the coils, a battery having its positive pole connected to the other end of said coil and its negative pole connected to the armature and to ground, an electrical connection between the tongue and one end of the other coil, a second battery having its negative pole connected to the other end of said second coil, a grounded electrical connection between the positive pole of said second battery and the connection between the negative pole of the first battery and the armature, and means operated by the movement of the armature when its magnet is energized, for dividing the apparatus into two independent circuits each including one of the batteries and one of the coils.

JOHN H. COOK.
